DESIGN FOR A WATCH BAND

Robert H. Preas, Vernal, Utah

Application September 27, 1944, Serial No. 115,483

Term of patent 14 years

(Cl. D45—4)

To all whom it may concern:

Be it known that I, Robert H. Preas, a citizen of the United States, residing at Vernal, in the county of Uintah and State of Utah, have invented a new, original, and ornamental Design for a Watch Band, of which the following is a specification, reference being had to the accompanying drawing, forming part thereof.

Fig. 1 is a perspective view of a watch band embodying my new design.

Fig. 2 is an end elevation.

Fig. 3 is a side elevation.

Fig. 4 is a top plan view.

I claim:

The ornamental design for a watch band, substantially as shown.

ROBERT H. PREAS.
